ABRAHAM ROTHWELL, OF BALTIMORE COUNTY, MARYLAND.

Letters Patent No. 86,102, dated January 19, 1869.

IMPROVED STONE-SAWING MACHINE.

The Schedule referred to in these Letters Patent and making part of the same.

To all whom it may concern:

Be it known that I, ABRAHAM ROTHWELL, of the county of Baltimore, and State of Maryland, have invented certain new and useful Improvements in Stone-Sawing Machine; and I do hereby declare that the following is a full, clear, and exact description thereof, reference being had to the accompanying drawings, and to the letters of reference marked thereon, which form a part of this specification, and in which—

Figure 1 represents a side elevation,

Figure 2, a top or plan view, and

Figure 3, a perspective view of feed-arrangement of my stone-sawing machine.

Similar letters of reference indicate corresponding parts in the several figures.

The object of my invention is to produce a machine, for cutting or sawing stone, which is capable of cutting two sides of an obelisk at one operation.

The nature of my invention consists in the employment of a stone bench, having a number of guides fixed thereon, in such a manner that, when a block of stone or marble is placed on said stone bench, the guides, when properly adjusted, may form guides for the saws.

It consists, further, in having the end-pieces of a saw-frame slotted, for the purpose of allowing the saws to move from side to side, said lateral motion being necessary, when the saws move in an oblique direction to the saw-frame.

The clamps of the saws are, for that purpose, extended through the slots of said end-pieces of saw-frame, and mounted by rollers. Said rollers bear against the outside end of saw-frame.

It also consists of a combined carriage and suspender-arrangement, whereby one end of the carriage may be brought down, effecting an incline, more or less, for the purpose of giving a swing to the frame, and discharging water and sand from the saw-cut.

It further consists in the employment of screw-spindles in connection with tooth-gearing, pawl, ratchet-wheel, and rock-shaft, for raising or lowering the carriage-frame; and, lastly,

It consists of a feed-device, hereinafter more fully set forth, whereby the cut of the saws may be regulated.

To enable others skilled in the art to which my invention appertains, to make and use the same, I will now describe its construction and operation.

In the accompanying drawings—

A represent a framing, which may be constructed in any proper manner, to support the working-parts.

B B represent two longitudinal pieces, which support the saw-frame C.

The pieces B B are allowed to move freely up and down in grooves in the frame A, as seen at i', fig. 1.

Slides or ways S' S' are secured to the longitudinal pieces B B, to carry wheels or guides 4 4, or the ways

S' S' may be made V-shaped, and corresponding projections fitting on the V-shaped pieces S' S', and attached to the saw-frame, may be employed.

Slide-nuts b c' are secured to the longitudinal pieces B B, and to the suspenders d e, which receive screw-spindles D D.

d e represent suspenders provided with extension-joints o o, said suspenders connected with slide-nut c' at h h; the other ends of suspenders d e are secured at g g.

Slide-nut c' plays up and down freely on screw-spindles D. Said screw-spindles D rest in step-boxes d' d' below. The upper end is provided with a mitre-wheel, V', which gears in the corresponding wheel V, on shaft W, bearing in boxes y y.

The end-pieces c c of the saw-frame C are slotted for the purpose of allowing clamps 8 to move freely from side to side, friction-rollers 3 3 being employed to facilitate the movements.

The saws F F are secured in the saw-frame by clamp 8, a pin passing through clamp and saw-holding both firmly together.

3 represents friction-rollers bearing against the outside of end-pieces of saw-frame C.

K is a rock-shaft, having its bearings in the frame A.

m is a lever, which has one end secured to the rock-shaft K, and slides up and down thereon. The opposite end of the lever m is slotted, and a pin passed through said slot into the saw-frame C.

n n are holes, into which the pin may be inserted to vary the feed of the saws.

On the upper end of the rock-shaft K is a lever, l, secured thereon, on the opposite end of which is a pin which works in a slot in the pawl o, which is supported by passing through a slot in the arm S, which is attached to the frame A.

The pawl o moves the ratchet-wheel n, on the shaft W, as the saw-frame is moved backward and forward, which gives a rotary motion to the shaft W and the pinion v, the latter gearing with the mitre-wheel V' on the end of the saw-spindle D, turning the latter, whereby the saw-frame C and the longitudinal pieces B B are lowered.

X X represent pins or guides fixed on the stone bench or bed-plate E, to act as guides for the saws F F.

The pins or guides X X are provided with rollers which fit over and extend concentrically the whole length of said rollers.

7 7 are holes for guides, to adapt the saws to the size of the obelisk.

M represents a block of marble.

10 represents the connecting-rod to crank-shaft.

The red lines in fig. 2 indicate the position of clamps 8 when the saw-frame is moved back.

The red lines in fig. 3 shows the carriage C lowered down, the arm m, on shaft K, following.

It will be observed that by operating the several

nuts *o o* on the suspenders *d e*, the inclination of the longitudinal pieces *B B*, and hence of the saw-frame *C*, may be varied, the pieces *B B* being hinged to the slide-nut *b*, which gives a swing to the frame, and facilitates the discharge of water and sand from the saw-cut.

It will also be observed that the slide-nuts *c' c'* project over the side pieces of the saw-frame *C*. By this arrangement all danger arising from the jumping of the saw-frame is obviated.

What I claim as my invention, and desire to secure by Letters Patent, is—

1. The saw-frame *C*, oblique saws *F F*, clamps *8 8*, and friction-rollers *3 3*, in combination with the adjustable guide *X X*, as and for the purpose set forth.
2. The hinged longitudinal pieces *B B*, sliding in

the frame *A*, in combination with the suspenders *d e*, *d e*, and swivel-nuts *o o*, as and for the purpose set forth.

3. The slide-nut *c'*, projecting over the saw-frame *C*, to prevent the jumping of said frame, as and for the purpose set forth.

4. The saw-frame *C*, in combination with the adjustable lever *m*, rock-shaft *K*, lever *l*, pawl *o*, ratchet *u*, pinions *V V'*, and screw-spindles *D D*, to lower the saw-frame, substantially as set forth.

In testimony that I claim the foregoing as my own, I affix my signature, in presence of two witnesses.

ABRAHAM ROTHWELL.

Witnesses:

C. ALEXANDER,
JOHN A. ELLIS.
